US0D1091826S

(12) **United States Design Patent** (10) Patent No.: **US D1,091,826 S**
(45) Date of Patent: ** Sep. 2, 2025

(54) **MEDICAL INSTRUMENT**

- (71) Applicant: **LSI Solutions, Inc.**, Victor, NY (US)
(72) Inventors: **Jude S. Sauer**, Pittsford, NY (US);
Matthew David DeClerck, Greece, NY (US)
(73) Assignee: **LSI Solutions, Inc.**, Victor, NY (US)
(**) Term: **15 Years**

(21) Appl. No.: **29/830,022**

(22) Filed: **Mar. 9, 2022**
